MISSOURI.

CRUDE-OIL BURNER.

No. 840,059.

Specification of Letters Patent.

Patented Jan. 1, 1907.

Application filed September 21, 1905, Serial No. 277,818.

To all whom it may concern:

Be it known that I, JOHN HARLEMAN, a citizen of the United States, residing at Kansas City, in the county of Jackson and State of Missouri, have invented certain new and useful Improvements in Crude-Oil Burners, of which the following is a specification.

This invention relates to crude-oil burners, and more especially to that type in which a downdraft is utilized to support combustion; and my object is to produce a burner of the character described which will operate efficiently and reliably, can be operated and controlled by any one capable of starting and maintaining a fire in an ordinary stove, may be easily and cheaply secured in or removed from operative position with relation to a furnace, and is of simple, strong, durable, and cheap construction.

With these and other objects in view, as hereinafter appear, the invention consists in certain novel and peculiar features of construction and organization, and in order that it may be fully understood reference is to be had to the accompanying drawings, in which—

Figure 1 represents a view taken approximately on the line I—I of Fig. 2. Fig. 2 represents a horizontal section taken on the line II—II of Fig. 1. Fig. 3 is a horizontal section taken on the line III—III of Fig. 1. Fig. 4 is a section taken on the line IV—IV of Fig. 2.

Referring now to the drawings in detail, 1 indicates the base, 2 the casing, and 3 the shell, of a hot-air furnace of the usual or any preferred type.

4 indicates the ash-pit opening; 5, the door thereof; 6, the casting connecting the shell and casing to provide the usual feed-door opening, and 7 the door controlling such feed-opening.

8 is the usual or any preferred type of fire-pot, and 9 is the grate.

10 indicates a shallow pan resting upon the grate and completely covering the same or not, as desired.

11 indicates the legs of a vaporizing-plate 12, said legs resting upon the bottom of the shallow pan about equal distances from its center and providing a chamber between the pan and vaporizing-plate for the play of the flames or fire. Vaporizing-plate 12 is provided with a central hole or opening 13 and with peripheral lugs 14, and disposed above

and centrally of plate 12 is a conical oil-distributer and vaporizer 15 of smaller diameter than plate 12 and supported a suitable distance above the latter by the legs or standards 16.

17 indicates a hood fitting down over the plate 12 and maintained concentrically thereof by the lugs 14, so as to form or provide a series of slots through which air, gas, and products of combustion may pass, and 18 indicates internal ribs thereof which rest upon the plate 12, the said ribs being of such length that the hood flanges down below said plate for a purpose hereinafter explained. The closed top of the hood is provided with a central opening 19, fitting slidably on the depending vertical arm of an elbow-coupling 20, said coupling being screwed or otherwise secured on an air-supply tube 21, extending radially outward through the feed-door opening of the furnace near the upper corner most remote from the hinged edge of the door.

22 indicates a strap engaging the air-supply tube and secured to the top portion of the casting 6 as a means of affording support to said tube. The outer end of the tube is provided with a flaring mouth 23, having a perforated end 24 and one or more adjustable buttons 25, whereby a rotary perforated valve-plate 26 is held in place, which under proper manipulation can be caused to vary the volume of or entirely cut off the supply of air to the air-tube.

27 indicates the oil-supply tube extending through the air-tube, one end of said oil-tube terminating vertically over the center of opening 19 in the hood, and therefore over the apex of the conical oil distributer and vaporizer, and the other end communicating with an oil-supply tank. (Not shown.)

28 indicates a valve to control the flow of oil through the pipe 27, and 29 indicates an opening or recess formed in the upper free corner of the feed-door 7 to accommodate the air-tube passing through the feed-opening. Where it is impracticable to secure the services of a machinist to form such opening or recess in said door the latter may be replaced by one cast with said opening in it. For new furnaces—that is, furnaces manufactured to accommodate this burner—the air and oil tubes may emerge at some other point of the furnace.

Assuming that the parts are assembled as

shown and described, the attendant first opens door 7 and pours a quantity of oil into the pan 10 and ignites such oil so that as it burns, the door being, of course, reclosed, the flames and other products of combustion impinge upon the plate 12 and its legs so as to quickly raise said plate to vaporizing temperature. The attendant then manipulates valve 28 to permit oil to flow through pipe 27 and drop down through the opening 19 onto the apex of conical plate 15, which divides the oil and causes it to flow outward thereon in different directions and eventually, if not converted into vapor by the heat of said plate, drop down on the highly-heated plate 12, which instantly converts it into vapor, which takes fire from the flame of the burning oil in the pan, it being understood that such vapor mixes with the oxygen of the air drawn into the furnace through the air-tube, the draft from the furnace-chimney (not shown) causing the air to enter the mouth 23 of the air-tube and be forcefully discharged downward therefrom upon the conical plate. As a result the air becomes thoroughly intermixed with the vapor of the oil, the mixture forming a combustible gas which burns fiercely, a portion of the flame passing under the conical plate and down through the hole or opening 13, where it turns outward and mixes with the balance of the flame which passes from the hood down through the slots formed by and between the hood and the plate, the entire volume of flame then passing down under the lower edge of the hood and heating the same, so that it shall coöperate with the vaporizing-plate proper in effecting the vaporizing function. After passing under and outward of the hood the flame and other products of combustion travel upward and escape from the furnace in the usual manner. The heat thus generated heats the air in the casing, from whence it passes to the apartments to be heated, and I have found from actual use that the burner operates efficiently and reliably and is economical in its consumption of oil.

To remove matter accumulating on any of the parts, the feed-door is opened and strap 22 removed. The operator then removes the oil-pipe and air-tube and coupling 20, the latter sliding out of opening 19 of the hood. The hood can then be engaged by a poker or other device and lifted out of the feed-door opening to give access to the vaporizing-plate and pan. The said plates and pan may be removed for cleaning purposes, if desired.

From the above description it will be seen that I have produced a crude-oil burner which is obviously susceptible of modification in minor particulars—for instance, to adapt it for use upon stoves of various kinds.

Having thus described the invention, what I claim as new, and desire to secure by Letters Patent, is—

1. A crude-oil burner comprising a casing, an imperforate pan therein, a vaporizing-plate supported by said pan at a distance above the same, a hood extending over said plate and having its lower edge below the same but above the pan, means for discharging air into said hood through the top of the same, and means for discharging oil upon said plate. 75

2. A crude-oil burner, comprising a casing, a pan therein, a vaporizing-plate supported by and above said pan, a hood suspended over and extending below said plate and terminating short of the pan, an air-supply tube 80 extending through the casing and adapted to receive air at its outer end and discharge it from its inner end into said hood and upon said plate, and an oil-supply pipe extending through the air-supply tube and terminating 85 at its inner end above the center of the vaporizing-plate.

3. A crude-oil burner, comprising a casing, a vaporizing-plate therein provided with a central opening, a hood suspended over and 90 extending below said plate, a conical plate within the hood supported by and above the vaporizing-plate and of smaller diameter than the latter, means to discharge oil down upon the apex of the conical plate, and means 95 to discharge air down upon said conical plate.

4. A crude-oil burner, comprising a casing, an imperforate pan therein, a vaporizing-plate supported by and above and of smaller diameter than said pan and provided with a central hole and with peripheral lugs, a conical plate supported by and above the vaporizing-plate and of greater diameter than said central hole, a hood suspended over said plates and fitting against the outer ends of said lugs and terminating a short distance below the same, means for discharging oil upon the apex of the conical plate, and means for discharging air down into the hood and upon said plates. 105

In testimony whereof I affix my signature in the presence of two witnesses.

JOHN HARLEMAN.
